UNITED STATES PATENT OFFICE.

GLENN G. WILMARSH, OF ALDENVILLE, PENNSYLVANIA, ASSIGNOR TO CLINTON CUT
GLASS COMPANY, OF ALDENVILLE, PENNSYLVANIA, A CORPORATION OF PENN-
SYLVANIA.

DESIGN FOR A GLASS VESSEL.

47,352.

Specification for Design.

Patented May 11, 1915.

Application filed October 13, 1914. Serial No. 866,547. Term of patent 3½ years.

To all whom it may concern:

Be it known that I, GLENN G. WILMARSH, residing at Aldenville, in the county of Wayne and State of Pennsylvania, have invented a new, original, and ornamental Design for Glass Vessels, of which the following is a specification, reference being had to the accompanying drawing, forming part thereof.

The figure is a perspective view of a glass vessel showing my new design.

I claim:—

The ornamental design for a glass vessel, as shown.

GLENN G. WILMARSH.
